(57) **CLAIM**

The ornamental design for a display screen with animated graphical user interface of a gaming machine as shown and described.

DESCRIPTION

FIG. 1 is a first image in a sequence for a display screen with animated graphical user interface of a gaming machine showing our new design;

FIG. 2 is a second image thereof; and,

FIG. 3 is a third image thereof.

The appearance of the graphical user interface sequentially transitions between the images shown in FIGS. 1-3. The process or period in which one image transitions to another forms no part of the claimed design. The peripheral broken line represents a boundary of the display screen with animated graphical user interface of a gaming machine and forms no part of the claimed design. The broken lines depicting the remainder of the display screen with animated graphical user interface of a gaming machine form no part of the claimed design.
